UNITED STATES PATENT OFFICE.

HERBERT J. SMITH, OF KEARNY, NEW JERSEY, ASSIGNOR TO AMERICAN FIBRE COOPERAGE COMPANY INC., OF DOVER, DELAWARE, A CORPORATION OF DELAWARE.

BARREL STAVE.

Application filed December 19, 1921. Serial No. 523,306.

To all whom it may concern:

Be it known that I, HERBERT J. SMITH, a subject of the Dominion of Canada, and resident of Kearny, in the county of Hudson and State of New Jersey, have invented certain new and useful Improvements in Barrel Staves, of which the following is a specification.

The invention relates to barrel staves formed of paperboard and the method of making the same, and has for its object to provide a stave comprising a body of paperboard, preferably including a series of plies of paperboard united by a suitable binder or adhesive, which latter will temporarily moisten the blank sufficiently to enable the same to be pressed into its ultimate form, which includes longitudinal and transverse curvatures and the narrowing of the staves from the middle toward the ends. Such formation of the stave is effected by pressing the softened paperboard blank to impart the desired curvature thereto, and at the same time forming in the body of the blank an intermediate longitudinal groove which increases in depth and width from the center toward the ends, and transverse grooves near the ends which increase in depth and width from the intersection thereof with the longitudinal grooves toward the lateral edges.

The invention is illustrated in the accompanying drawing, in which:

Figure 1 is a perspective view of a suitable paperboard blank for forming a stave;

Fig. 2 is a plan view of a complete stave looking toward the inside;

Fig. 3 is an end elevation of the same;

Fig. 4 is a plan view of the stave from the outside;

Fig. 5 is a fragmentary sectional perspective view showing the mode of applying a hoop and head to the barrel, and

Fig. 6 is a perspective view of the complete barrel.

Referring to the drawings, 1 indicates the paperboard blank for forming a single stave, the same preferably comprising a series of plies of rectangular sheets of paperboard, united by a suitable adhesive, such, for example, as silicate of soda, which will have the effect of first softening the blank to render the same more or less plastic and pliable, and subsequently to set or harden and retain the blank in the ultimate form imparted thereto by the succeeding operations.

While the blank is still plastic or soft, due to the action of the adhesive, it is placed in a suitable press, which reduces the blank to its final stave-like form, namely, with the proper bilge produced by imparting a longitudinal curvature from end to end and a transverse curvature from side to side. During the pressing operation there is formed in the blank a median longitudinal groove 2, which increases in depth and width from the center of the blank toward each end, said groove comprising a relatively narrow shallow middle portion and outwardly flaring deepening end sections 3 which have the effect of producing the necessary taper of the stave from the middle section toward the ends. In addition to these grooves 2, there is also formed during the pressing operation transverse grooves 4 in the respective ends of the staves, which grooves increase in depth and width from the intersections thereof with the longitudinal grooves toward the lateral edges of the blank and provide inwardly projecting ledges 5 to support the barrel heads 6 and channel-like elements 7 to receive the hoops 8. These longitudinal and transverse grooves also constitute material reinforcing or strengthening elements for each stave so that the staves may be handled and shipped without danger of deforming the same.

In this particular form and structural arrangement of the staves as illustrated, eight units are sufficient to form a barrel, and when assembled in the usual manner and the heads 6 and hoops 8 applied in accordance with the standard practice, a very strong and light barrel, as illustrated in Fig. 6, results. When the staves are thus made up into a barrel, the inwardly projecting portions of the staves formed by the deepened end sections 3 of the grooves 2 overhang the heads 6 and serve to lock them in place on the ledges 5.

What I claim is:

1. A barrel stave comprising a blank of paperboard having a continuous intermediate longitudinal groove therein increasing in depth and width from the center toward each end of the blank.

2. A barrel stave comprising a blank of paperboard having an intermediate longitudinal groove therein increasing in depth and width from the center toward each end of the blank, and transverse grooves near

each end increasing in depth and width from the intersection thereof with the longitudinal groove to the lateral edges.

3. A barrel stave comprising a blank 5 formed of several plies of paperboard united by an adhesive, said blank having an intermediate longitudinal groove therein increasing in depth and width from the center toward each end of the blank.

10 4. A barrel stave comprising a blank formed of several plies of paperboard united by an adhesive, said blank having an intermediate longitudinal groove therein increasing in depth and width from the center to-

ward each end of the blank, and transverse 15 grooves near each end increasing in depth and width from the intersection thereof with the longitudinal groove to the lateral edges.

5. A barrel stave comprising a blank of 20 paper board having an intermediate longitudinal groove, and transverse grooves near each end increasing in depth and width from the intersection thereof with the longitudinal groove to the lateral edges.

Signed at New York, in the county of 25 New York, and State of New York this 8th day of December, A. D. 1921.

HERBERT J. SMITH.
